(57) **CLAIM**

The ornamental design for a glass cleaning device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of our new design for a glass cleaning device;

FIG. 2 is a front view thereof;

FIG. 3 is a back view thereof;

FIG. 4 is a left end view thereof;

FIG. 5 is a right end view thereof;

FIG. 6 is a top view thereof;

FIG. 7 is a bottom view thereof; and,

FIG. 8 is a perspective, exploded view of the glass cleaning device.

Portions of the glass cleaning device illustrated in grey overlay and broken lines are for illustrative purposes and form no part of the claimed design.
